UNITED STATES PATENT OFFICE.

ARTHUR COULOMBE AND ELCYDAS LACROIX, OF WOONSOCKET, RHODE ISLAND.

VINEGAR-GENERATOR.

No. 799,832.

Specification of Letters Patent.

Patented Sept. 19, 1905.

Application filed May 22, 1905. Serial No. 261,701.

To all whom it may concern:

Be it known that we, ARTHUR COULOMBE and ELCYDAS LACROIX, subjects of the King of Great Britain, residing at Woonsocket, 5 county of Providence, State of Rhode Island, have invented certain new and useful Improvements in Vinegar-Generators; and we do hereby declare that the following is a full, clear, and exact description of the invention, such 10 as will enable others skilled in the art to which it appertains to make and use the same.

This invention relates to new and useful improvements in vinegar-generating apparatus; and it consists in certain features of novelty 15 relating to the construction and operation thereof, whereby an efficient and economical device for the purpose described is provided, which is simple, durable, and economical in construction, and which may be used for an 20 indefinite period without danger of rusting.

The object of the invention is to provide means whereby vinegar may be produced from an alcohol mixture, which passes into the generating apparatus, hereinafter described, and 25 passes from a higher to a lower plane therein, preferably in a thin sheet, which is exposed to the action of oxygen admitted to the interior of the generator for the purpose of producing the vinegar.

30 Referring to the accompanying drawings, in which similar numerals of reference indicate corresponding parts in all the views, Figure 1 is a longitudinal vertical sectional view taken approximately centrally through the generating apparatus forming the subject-matter of this invention and through a fragment of an elevated tank, in which may be placed the mixture of alcohol and sour beer which is used in manufacturing the vine- 35 gar. Fig. 2 is a transverse sectional view on line 2 2 of the complete apparatus. Fig. 3 is a fragmentary detail sectional view taken relatively on line 3 3 of Fig. 1. Fig. 4 is a detached detail of one of the shelves hereinafter referred to, and Fig. 5 is a fragmentary view illustrating the connection between the clamping-bars hereinafter described.

Referring to the parts, 1 refers to the casing of the generator, which casing comprises 40 the side plates or boards 2, a bottom plate 3, with the top plate 5, which plates are preferably formed of wood, and are held in position, as shown in Figs. 1 and 2, by means of the binding-timbers 6 and 7, which are united,

as shown in Figs. 2 and 3, and are locked by 55 means of wedges 8, which are projected through the elongated slots 9 to lock said members in position, thereby holding the bottom, sides, and top plate of the generating-case in position. It will be noted that the 60 bottom plate is supported in position upon the transversely-extending cleats or ledges 10, so as to be removable when desired. Above the bottom plate there are arranged a series of obliquely and oppositely disposed shelves 65 12. Said shelves are supported upon and preferably connected to the wedge-shaped supporting-plates 13, arranged in pairs at the ends of said shelves to form supports therefor, there being a space 14 between the lower 70 end portion of each shelf 12 and the side wall adjacent thereto. The shelves 12 are provided with transversely-extending shallow channels 15, formed in the upper face thereof, while perforations 16 are provided in the ma- 75 terial of the plates 12 between said channels 15.

The walls of the generator-case are perforated, as shown at 17, for the admission of oxygen, and extending upwardly and relatively from the central portion of the generator-case is a tube 18, as shown, which tube 80 communicates with the interior of the generator-case and leads to atmosphere. In addition to the tube 18 there is provided a second tube 19, in which is positioned the discharge- 85 spout 20 of the funnel 21, there being an air-space 22 between the funnel-spout 20 and said tube 19.

Above the funnel 21 is a tank or receptacle 23, in which the alcohol solution is placed. 90 The tank 23 is provided with a spigot 24, which is controlled by means of the valve 25, a second spigot 26 being located at the lower end of the generator-case, as shown in Fig. 3.

It will be noted that in the device herewith 95 illustrated a continuous zigzag passage is provided from the discharge-spout of the funnel to the discharge-spigot 26 at the lower end of the generator-case, and it is preferred that the angle of inclination of the shelves 12 shall 100 be such that there shall be but a slight fall between the upper and lower ends thereof, so that the progress of the alcohol solution over such shelves shall be somewhat retarded.

The operation of the device is as follows: 105 The apparatus being placed in the position shown in Fig. 1, the alcohol solution is admitted to the interior of the generator-case

through the funnel 21, falling upon the upper shelf 12 and distributing itself over the surface of said shelf, some of the alcohol being retained temporarily in the channels 15, with 5 a relatively small proportion of the alcohol passing through the perforations 16 in said shelf 12, while the remainder of the alcohol passes along the entire length of said shelf and through the opening 14 onto the next 10 lower shelf, upon which the alcohol is distributed in the same manner, passing into and past the channels 15 through perforations 16, &c., to the next lower shelf, and thus the passage of the alcohol mixture from the top 15 to the lower portion of the generator-case progresses. Oxygen is admitted through the perforations 17, referred to, and coming into contact with the alcohol mixture results in the production of vinegar without the aid of 20 the shavings which have been commonly used and to supersede which the present invention is designed.

Owing to the fact that the generator-case is formed of separate boards or plates, as 25 shown, which are held in position by means of non-metallic locking means, and the fact that the shelves 12 are supported upon the non-metallic wedge-shaped supporting means 13, which are longer than said shelves, it is 30 evident that the generating apparatus herewith shown and described may be readily taken apart for cleansing when desired and may be easily reassembled by unskilled labor.

Having described our invention, what we 35 claim, and desire to secure by Letters Patent, is—

1. In a vinegar-generator, a case, a series of oppositely and obliquely disposed shelves having transversely-extending shallow chan-

nels formed in said shelves, with a plurality 40 of perforations in said shelves between the channels.

2. In a vinegar-generator, a case the inner faces of which are non-metallic, oppositely-disposed pairs of wedge-shaped supporting 45 members, and a plurality of inclined shelves supported between the pairs of supporting members.

3. In a vinegar-generator, a case the inner faces of which are non-metallic, oppositely- 50 disposed pairs of wedge-shaped supporting members, and a plurality of inclined shelves supported between the pairs of supporting members, said shelves being of less length than the supporting members.

4. In a vinegar-generator, a case the inner faces of which are non-metallic, oppositely-disposed pairs of wedge-shaped supporting members, and a plurality of inclined, perforated and channeled shelves supported between the pairs of supporting members. 55

5. In a vinegar-generator, a non-metallic, collapsible, case, locking means therefor, and obliquely oppositely-disposed, channeled and perforated shelves arranged in different planes 60 in said case, the channels extending transversely of said shelves and there being a plurality of perforations through the shelves intermediate said channels.

In witness whereof we have hereunto set 70 our hands in the presence of two witnesses.

ARTHUR COULOMBE.

ELCYDAS ^{his} ~~mark~~ LACROIX.
